HOSIERY HAMPER

Thomas H. Davis, Brooklyn, N.Y., assignor to Davis Products Corp., Brooklyn, N.Y., a corporation of New York

Application May 15, 1959, Serial No. 55,918

Term of patent 3½ years

(Cl. D58—4)

Fig. 1 is a front perspective view of a hosiery hamper embodying my new design; and

Fig. 2 is a similar view thereof shown in open position.

The dominant features of my design reside in the portions shown in full lines.

The configuration of the pattern comprising the surface ornamentation is nodular.

The rear is plain and the side not shown is substantially the same as the side shown.

I claim:

The ornamental design for a hosiery hamper, as shown and described.
